GUN WITH RECOILING BARREL.

1,208,414.

Specification of Letters Patent. Patented Dec. 12, 1916.

Application filed March 27, 1915. Serial No. 17,336.

To all whom it may concern:

Be it known that I, KARL VÖLLER, engineer, a subject of the German Emperor, residing at 12 Scharnhorststrasse, Dusseldorf, 5 Germany, have invented certain new and useful Improvements in Guns with Recoiling Barrels; and I do hereby declare the following to be a full, clear, and exact description of the invention, such as will enable others skilled in the art to which it 10 pertains to make and use the same.

My invention relates to a gun having a recoiling barrel and has for its object to arrange the trunnions of a gun of this kind in 15 such a position that no part of the recoiling system in recoiling passes beyond the trunnions.

An embodiment of my invention is shown 20 on the accompanying drawings in which— Figure 1 is a side elevation of a gun constructed according to my invention. Fig. 2 is a plan view. Fig. 3 is a cross section in the line 3—3 of Fig. 1.

The gun barrel *a* is movable in a well 25 known manner within the cradle *a*¹ and may be elevated about the trunnions *b* resting in bearings *c* connected with the gun carriage *d*. The latter rests on the platform *e* and is provided with an elevating mechanism *f* of 30 any known construction. The gun carriage is provided with a vertical pivot *g* engaging a corresponding bearing in the platform so that the gun carriage with the gun may be adjusted in a lateral direction by means of 35 the mechanism *g*¹.

Fig. 1 shows by dotted lines the gun in different positions of elevation and it will be seen that the angle of elevation may be from 0° to 90°.

40 The described arrangement has the advantage that the trunnions may consist of a single bolt *b* passing through both bearings *c*. It is evident that the recoiling power is at all elevations of the gun always directed 45 exactly toward the axis of the trunnions, and if the trunnions or the bolt *b* are arranged at a small height over the platform *e* the recoiling power is always directed nearly toward the same point of the platform. 50 Thereby it will be possible to make the platform very rigid and strong against the force of the recoil without unduly increasing its weight.

The pivot *g* may be arranged immediately below the point resisting the recoiling power 55 or at least in the neighborhood of that point, so that the chief resistance point is always nearly at the same place even when the gun has been swung about a large angle in a horizontal direction. 60

My invention is especially adapted for guns in which the platform may be transported in connection with the gun barrel or separated therefrom. However my invention is also applicable to guns having a fixed 65 position or to guns with a wheel carriage.

Having thus described my invention what I claim is:

1. In combination, a recoiling barrel, a cradle therefor, and trunnions for the cradle 70 located in rear of the limit of travel of the barrel in recoiling and in the plane of the travel thereof.

2. In combination, a recoiling barrel, a cradle therefor having extensions the ends 75 of which are beyond the limit of travel of the barrel in recoiling, and trunnions for said extensions at the outer ends thereof, the axial line of said trunnions being intersected by the axial line of said barrel in all 80 positions of the latter.

3. In combination, a recoiling barrel, a cradle therefor having extensions the ends 85 of which are beyond the limit of travel of the barrel in recoiling, and trunnions for said extensions at the outer ends thereof, a carriage having bearings for the trunnions, and a vertical pivot for the carriage, in approximately the same vertical plane with 90 said bearings.

4. In combination, a recoiling barrel, a cradle therefor having extensions the ends 95 of which are beyond the limit of travel of the barrel in recoiling and in the plane of the travel thereof, a carriage having bearings for the trunnions, and a vertical pivot for the carriage located in proximity to the pivot of the cradle.

5. In a gun having a recoiling barrel the combination of a cradle; lateral guideways 100 connected with the cradle for guiding the recoiling barrel and trunnions at the outer end of these lateral guideways, the common plane of the latter intersecting the axial line of said trunnions. 105

6. In a gun having a recoiling barrel the

combination of a cradle, lateral guideways connected with the cradle for guiding the recoiling barrel and a horizontal bolt forming trunnions at the outer end of these lateral guideways, the common plane of the latter intersecting the axial line of said trunnions.

In testimony whereof, I have signed this specification in the presence of two subscribing witnesses.

KARL VÖLLER. [L.S.]
